(57) **CLAIM**

The ornamental design for a display with portion of a graphical user interface, as shown and described.

DESCRIPTION

A portion of the disclosure of this patent document contains material which is subject to copyright protection. The copyright owner has no objection to facsimile reproduction by anyone of the patent document or the patent disclosure, as it appears in the Patent and Trademark Office patent file or records, but otherwise reserves all other copyright rights whatsoever. The following notice applies to the drawings that form a part of this document: Copyright © 2011, Inkling Systems, Inc.

The sole FIGURE is a front view of a display with portion of a graphical user interface showing my new design.

The broken lines in the drawing represent parts of the display with portion of a graphical user interface that form no part of the claimed design.
